UNITED STATES PATENT OFFICE.

JOHN T. WILSON, OF ALAMEDA, CALIFORNIA.

PACKING-RING FOR PISTONS.

1,290,456.

Specification of Letters Patent.

Patented Jan. 7, 1919.

Application filed August 29, 1916. Serial No. 117,550.

To all whom it may concern:
Be it known that I, JOHN T. WILSON, a citizen of the United States, residing at Alameda, in the county of Alameda and State of California, have invented certain new and useful Improvements in Packing-Rings for Pistons; and I do hereby declare the following to be a full, clear, and exact description of the invention, such as will enable others skilled in the art to which it appertains to make and use the same.

The object of my invention is the provision of an improved metallic packing ring for engine pistons actuated by any power whatever, explosive gas, compressed air, or steam, but which shall be especially adapted for use in connection with gas-engine pistons, where frequent renewals of the rings are necessary.

It is desirable that a packing ring for gas-engine pistons shall have a joint plate which will maintain its proper position relative to the ends of the ring when the ring is detached and being shipped and handled, as well as be held against radial displacement relative to the ends of the ring when in use; and further, on account of the small dimensions of the ring, it shall not be weakened by the presence of holes to receive retaining rivets or other fastening means.

With these ends in view, my invention consists in a resilient packing ring having tongues loosely united by a joint plate provided with a base and parallel wings or flanges, the tongues being located between the wings, and the tongues and wings so fashioned that they will interlock and permit of longitudinal movements only, of the tongues relatively to the wings, or vice versa.

It further consists in certain novelties of construction and the combination of parts as herein set forth and claimed.

The accompanying drawing illustrates three examples of the embodiment of the invention constructed, and the parts combined according to the best methods of procedure I have so far devised for the purpose.

Figure 1 is a side view in elevation of one form of the improved packing ring with the parts in the positions they occupy when the ring is contracted.

Fig. 2 is a cross-section on line 2—2 of Fig. 1.

Fig. 3 is a top-plan view of Fig. 1 showing the ring expanded. 55

Fig. 4 is a perspective view of the joint plate and ends of the ring shown by Fig. 3.

Fig. 5 shows the ends of the expanded ring and the joint plate in position to receive the tongues. 60

Figs. 6 and 7 illustrate the second example or form of the packing ring.

Figs. 8 and 9 illustrate the third example or form.

In Figs. 6 and 8 the rings are slightly expanded and Figs. 7 and 9 are views like Fig. 5.

In each of the examples A designates the body of the ring; B the tongues; C the shallow seats at the inner surfaces of the ends 70 of the rings; D the base of the joint plate; and E, the parallel flanges, or wings, integral with the base.

The joint plate is united to the tongues by expanding the resilient ring and allowing 75 the tongues to enter the space between the flanges or wings when the ring contracts, the free ends of the base frictionally engaging the shallow seats C, at the same time.

On reference to Fig. 2, it will be seen that 80 the cross-section of the wings and of a tongue between them is the same as the cross-sectional dimensions of the body of the ring.

To interlock the tongues and wings so the tongues can move longitudinally only, relatively to the wings and base, and vice versa, and in no other direction, novelties in the shapes of the wings and tongues are introduced. 85

In Figs. 1 to 5, the sides of each tongue are 90 provided with beveled surfaces 1 extending outwardly toward each other, and the wings provided with inner beveled surfaces 2 extending inwardly and away from each other, matching the beveled surfaces of the tongues 95 so they are in frictional contact and interlock against relative movements in all directions except longitudinally relative to one another.

In Figs. 6 and 7, the beveled surfaces 3 of 100 the tongues are of less area and extend only part way down the opposite sides thereof, and in the inner surfaces of the wings have beveled surfaces 4 adjacent to their outer edges only, as clearly shown.

In Figs. 8 and 9, the outer, longitudinal

edges of the tongues are provided with seats 5, formed by removing portions of the metal, and the wings are fashioned with inwardly projecting lugs 6 at their outer edges, which 5 loosely and frictionally engage the said seats.

The principle is the same in each example, the tongues and joint plate being united so that longitudinal movements only, of the tongues relative to the wings, or vice versa, 10 is possible.

The method of fashioning the several parts is well known to those skilled in the arts. The joint plate is preferable of bronze or steel, and the desired shapes of the inner 15 surfaces of the wings may be attained by milling the same after cutting a longitudinal channel to form the wings or flanges.

The body of the rings is of cast metal, and the scale on the inner surface is retained, except at the ends, where it is removed to form 20 the seats for the ends of the base of the joint plate. The tongues are milled to provide the beveled surfaces in examples one and two, and the seats in the third example, in 25 a well-known way.

After a joint plate has been applied to the ends of the ring, the same is contracted to the proper tension and the outer and side surfaces ground to uniform dimensions.

30 From the foregoing description taken in connection with the drawing, it becomes obvious that I have produced a resilient packing ring of the greatest possible strength and of very simple construction. The joint 35 plate can not become detached before or after its application to the piston. A tight joint with the inner surface of the cylinder

will be secured, and the ends of the ring and joint plate are held against relative radial displacement in use, insuring an even wear 40 of the parts as well as a tight joint.

What I claim is:

1. A packing ring having tongues, and a joint plate with a base and wings; the space between the wings at their outer edges being 45 narrower than the space between the wings where they join the base, and the outer or bearing edges of the tongues being narrower than the inner edges, whereby the tongues and wings interlock so neither tongue can 50 move radially relative to the joint plate.

2. A packing ring having centrally disposed tongues integral with the ring, and a joint plate with a base and wings, said wings being parallel, at the edges of the 55 plate, and spaced apart to receive the tongues between them, the inner surface of each wing being a beveled surface and each tongue provided with beveled surfaces matching the inner beveled surfaces of the 60 wings.

3. A packing ring having tongues, and a joint plate with a base and wings, the inner 65 surface of one wing having a beveled surface and each tongue provided with a beveled surface matching the beveled surface of the wing, so that the tongues and wings will interlock, and permit longitudinal movement of the tongues and wings relatively to one another and prevent radial displacement 70 of the tongues and wings relatively to one another.

In testimony whereof I affix my signature.
JOHN T. WILSON.
